UNITED STATES PATENT OFFICE.

CHARLES B. McDONALD AND CHARLES D. McDONALD, OF CHICAGO, ILLINOIS, ASSIGNEES TO McDONALD MACHINE COMPANY, OF CHICAGO, ILLINOIS, A CORPORATION OF ILLINOIS.

CAN-TESTING MACHINE.

945,573.

Specification of Letters Patent. Patented Jan. 4, 1910.

Application filed October 27, 1908. Serial No. 459,679.

To all whom it may concern:

Be it known that we, CHARLES B. McDONALD and CHARLES D. McDONALD, both citizens of the United States, both residing in Chicago, in the county of Cook and State of Illinois, have invented certain new and useful Improvements in Can-Testing Machines, of which the following is a specification.

This invention relates to can testers of the general style shown and described in application Serial No. 436,009, filed June 1, 1908; and the object of the present invention is to simplify the mechanism described in said application by eliminating all of the pressure actuated devices, save one, thereby enabling all of the cans carried by the testing wheel to be brought successively into register with a single pressure actuated device, which is adapted to be influenced by a reduction in pressure below the normal, in such manner as to discard defective cans at a predetermined point in the travel of the testing wheel.

The invention further relates to certain improved features in the construction and operation of the pressure actuated mechanism, and in the means employed for bringing the cans successively into register therewith.

Further objects will appear from a detailed description of the invention, which consists in the features of construction and combination of parts hereinafter described and claimed.

In the drawings, Figure 1 is a sectional elevation of the pressure actuated mechanism in released position; Fig. 2 a similar view of the same, showing the parts in engaged position; Fig. 3 an end elevation of the can head on the actuating pin; Fig. 4 a face view of the revoluble cam; Fig. 5 a sectional view of the cone bearing for the testing wheel, together with portions of the wheel; Fig. 6 a cross sectional view of the same; and Fig. 7 an enlarged detail of one of the sealing heads.

In describing the features of the present invention, it is not deemed necessary to enter into a full description of the construction and arrangement of the testing wheel, the sealing heads and the can discharge chute, all of which are fully described in the application previously referred to.

As shown in Fig. 1, the testing wheel comprises a rim 8, which is connected with a hub 9 by means of spokes 10. The hub is keyed to a shaft 11, which shaft is journaled within a fixedly mounted cone 12, which cone is surrounded by a ring 13 which is beveled on its inner face to fit the cone and which is secured to a flange 14 on the hub, by means of bolts, or in any other suitable manner. These features are fully described in the application referred to, and further description is deemed unnecessary.

The cone has formed therein an air supply passage 15, which receives air under pressure from a pipe 16, and the air supply passage is adapted to register with any one of a plurality of passages 16^a which communicate with a series of sealing heads 17 by means of sections of rubber hose 18. In order to equalize the amount of air supplied to each can, each of the air passages leading to the sealing heads has entered thereinto an adjustable check valve 18^a. It will be understood that each of the sealing heads is thus provided with a pipe which is adapted to receive air under pressure from the main supply at a suitable point in the revolution of the wheel. Each of the sealing heads 17 cooperates with a clamping head 18^a adapted to be actuated by means of suitable links and levers 19, actuated by cams or other like mechanism. The method of actuating these clamping heads is fully explained in the application above referred to.

In addition to the pressure supply passage, the cone is provided with an outlet passage 19^a, which communicates with a tester pipe 20 leading to the pressure actuating tester 21, which more especially forms the subject matter of the present invention. The supply passage is so located as to fill each of the cans with air pressure immediately after its engagement by the clamping head, which pressure, thus supplied, will be retained within the can, if the latter be perfect, until the passage 16^a has almost completed its circle of travel, and is brought into register with the outlet passage 19^a which communicates with the testing device. If, during the course of its travel, the can has allowed a reduction of pressure, due to leakage, this fact will be recorded by the tester and suit-

able mechanism set in action, whereby such defective can will be thrown out at a suitable point of discharge.

The testing mechanism of the present invention is inclosed within a box 22, and is in character as follows: The pipe 20 communicates with a bowed tubular gage spring 23 of the usual character, which is adapted to expand or straighten under the influence of pressure, as shown in Fig. 2, its normal curvature being indicated in Fig. 1. The free end of the spring has pivoted thereto a link 24, which engages the short arm 25 of an L lever 26 which is pivoted at its elbow 27. The lever 26 abuts against a spring 26^a carried by a slide plate 26^b, which is adjustably mounted within a guideway 26^c. The position of the slide plate can be adjusted by turning a thumb screw 26^d, which can be locked in adjustable position by means of a jam nut 26^e. The long arm of this L lever greatly exceeds the short arm in length, so that very small variations in the position in the free end of the bowed gage spring will be magnified many times at the end of the long arm of the L lever. The L lever is connected by means of a rod 28, with a trip finger 29 which is pivoted to a bracket 30 at a point near the upper end of the finger, whereby movements of the rod 28, imparted to the short end of the pivoted finger, will be magnified or accentuated at the long end of such finger, which is provided with a hook 30^a which is adapted 35 to engage a lug 31 which outwardly projects from the end of an actuating pin 32, which is slidably mounted within a sleeve or guideway 33 and is provided, on its lower end, with a cam head 34, whose side face 35 is 40 flattened in the form shown in Fig. 3, and is adapted, when the pin is dropped, to engage a spring supported pin 36 which outwardly projects from the inner face of a cam wheel 37. The cam wheel is in the 45 form shown in Fig. 4, and is provided, in addition to the pin 36, with a stop pin 38 which lies slightly nearer the center of the cam wheel. The cam wheel is mounted upon a shaft 39, driven by means of bevel 50 pinions 40, or other suitable gearing, at such speed that the cam wheel will be completely revolved by the passage of each cam. In other words, if the tester wheel is provided with forty sealing heads adapted 55 to receive forty cans, the cam wheel will be revolved forty times during the revolution of the tester wheel. The cam wheel is adapted to engage an inwardly extending pin 41 on the actuating pin, and the formation 60 of the surface of the cam is such that the actuating pin will be raised slightly with each revolution of the cam wheel.

The spring supported pin 36 is adapted to engage the upper end of a lever 42, which is 65 pivoted at the point 43 and is adapted to ac-

tuate a discharging runway like that shown in the application previously referred to. The upper end of the lever normally underlies the pivoted catch finger 44, which is held in engagement with the lever by means of a 70 spring 45. The catch finger is provided with a depending tooth 46 which, when the lever 42 is thrust back, as shown in Fig. 1, will hold the lever against the return movement until the revolution of the cam wheel 75 has brought the stop pin 38 under the end of the catch finger 44, which rises as the stop pin passes thereunder and allows the lever 42 to resume its normal position.

In use, the cans are fed in succession to 80 the tester wheel in any suitable manner, and are successively clamped in position against the sealing heads. Each can in turn receives its charge of air under pressure and is carried around to practically a complete revolution until the can is brought into communication with the tester. If the pressure within the can be reduced, by leakage, the gage spring will be moved from the position shown in Fig. 2 to the position shown in Fig. 1, which movement is made possible by a slight lifting of the actuating pin with each revolution of the cam wheel. As the pin is lifted, the hook 30^a on the trip finger 29 will be released from engagement with the tooth 85 31, which allows the parts to assume a position shown in Fig. 1, and allows the actuating pin to fall by gravity, so that its cam head 35 will occupy a position within the course of travel of the spring supported pin 90 36. When said pin is brought into contact with the cam surface 35, it will be thrust back against the lever 42, which lever will be locked against a return movement by the catch finger 44. This movement of the lever 95 42 serves to actuate suitable discharging mechanism, preferably of the style shown in the application previously referred to, whereby the defective can will be thrown out and discharged. If, on the other hand, a perfect 100 can be brought into register with the tester, the proper degree of pressure will be maintained in the gage spring, which will be bowed as indicated in Fig. 2, so that, when the actuating finger is raised by the revolution of the cam wheel, the trip finger 29 will 105 maintain its same position and engage and suspend the actuating pin after it has been released by the cam wheel.

In testing cans of different sizes, it is necessary to regulate the degree of pressure of the lever 26 so that, regardless of the size of the cans being tested, the lever will have just a sufficient amount of movement to effect the suspension of the pin 32; and, in order to 110 adjust the mechanism to such varying conditions and prevent an excess of movement which would carry the hooked finger 30^a too far under the tooth 31, the adjusting screw is provided by the regulation of which 115 120 125 130 135

the operator can equalize the movements under all conditions.

The invention is one which greatly simplifies the construction of a can testing machine, in that all of the testing is done by the same mechanism, which can thus be maintained in a perfect state of efficiency at all times, and is a much more satisfactory method of making the test than by providing each of the sealing heads with its own individual testing mechanism, which unnecessarily complicates the machine and greatly increases the possibility of disarrangement or mal-adjustment of the parts.

15 The testing mechanism is one which is able to detect very small leaks, which would ordinarily not be detected by the usual methods employed in can testing, and at the same time the work will be performed rapidly and automatically.

Although a bowed gage spring has been described and illustrated as the means for detecting variations in pressure, it is obvious that other means could be employed to 20 effect a similar result, so that, unless otherwise specified, it is not the intention to limit the claims strictly to the use of a bowed gage spring of the character described.

What we regard as new and desire to secure by Letters Patent is:

30 1. In a can testing machine, the combination of a tester wheel provided, around its rim, with a plurality of sealing heads and clamping heads, pipes connecting the sealing heads with the hub of the wheel, a bearing for the hub provided with inlet and outlet passages adapted to be brought into communication with the pipes leading to the sealing heads, means for admitting the fluid under 35 pressure to the inlet passage, a testing device in communication with the outlet passage, said testing device comprising mechanism movable by changes in pressure, and a lever connected with said pressure actuated mechanism adapted to accentuate or magnify the movements thereof, a trip finger connected with said lever, an actuating pin adapted to be engaged by said trip finger and held elevated when cans of a selected 40 type are brought into register with the testing device, and adapted to release the pin when cans of a different type are brought into register, and means actuated by movements of the actuating pin for throwing out defective cans, substantially as described.

45 2. In a can testing machine, the combination of a tester wheel provided, around its rim, with a plurality of sealing heads and clamping heads, pipes connecting the sealing heads with the hub of the wheel, a bearing for the hub provided with inlet and outlet passages adapted to be brought into communication with the pipes leading to the sealing heads, means for admitting fluid under 50 pressure to the inlet passage, a testing

device in communication with the outlet passage, said testing device comprising a mechanism movable by changes in pressure, and a lever connected with said pressure actuated device adapted to accentuate or magnify the 55 movements thereof, a cam wheel adapted to be rotated with the passage of each can, a pin on said cam wheel adapted to be brought into engagement with the actuating pin when the latter is released by the trip finger, and means actuated by the movement of 60 said pin on the cam wheel for throwing out cans of a selected type, substantially as described.

3. In a can testing machine having sealing heads and clamping heads, a testing device comprising a bowed tubular gage spring, a lever connected with the free end of said gage spring, a trip finger connected with the lever, an actuating pin normally 65 adapted to be supported by the trip finger, and means actuated by movements of the actuating pin for discharging defective cans, substantially as described.

4. In a can testing machine, a testing device comprising a bowed tubular gage spring, a lever connected with the free end of said gage spring, a trip finger connected with the lever, an actuating pin normally 70 adapted to be supported by the trip finger, a cam wheel adapted to be revolved by the passage of each can, a spring supported pin carried by the cam wheel and adapted to be moved when engaged by the released actuating pin, a lever adapted to be engaged by 75 said pin, a catch adapted to engage and hold the lever when released by the pin for actuating the can discharging mechanism, and a stop finger on the cam wheel adapted to release the lever from engagement by said 80 catch, substantially as described.

5. In a can testing machine having sealing heads and clamping heads, a testing device comprising a member adapted to be moved by changes in pressure, a lever having a 85 long arm and a short arm, the latter being engaged by said pressure actuated member, a trip finger connected with the long arm of said lever, an actuating pin adapted normally to be engaged by said trip finger, a cam wheel in engagement with the actuating pin and adapted to raise the same with each revolution sufficiently to permit disengagement of the trip finger, a spring supported pin carried by the cam wheel and adapted to be engaged by the end of the trip finger when released, and means actuated by the engagement of said pin for throwing out cans of any selected type, substantially as described.

6. In a can testing machine having sealing heads and clamping heads, a testing device comprising a member adapted to be moved by changes in pressure, a lever adapted to be 90 actuated by the movements of said member,

means for regulating and limiting the movements of said lever, a hooked trip finger connected with said lever and adapted to be actuated thereby, a pin adapted to be engaged and held by said hooked finger, and mechanism actuated by the movements of said pin, for throwing out cans of a selected type, substantially as described.

7. In a can testing machine having sealing heads and clamping heads, a testing device comprising a member adapted to be moved by changes in pressure, a lever having a long arm and a short arm, the latter being engaged by said pressure actuated member,

10 means for adjusting and limiting the movements of the long arm of the lever, a trip finger connected with the long arm of the lever, an actuating pin adapted to be normally engaged by said trip finger, a cam

15 wheel in engagement with the actuating pin and adapted to rise with each revolution sufficient to permit disengagement of the trip finger, a spring supported pin carried by the cam wheel and adapted to be engaged by the end of the trip finger when re-

leased, and means actuated by the engagement of said pin, for throwing out cans of a selected type, substantially as described.

8. In a can testing machine having sealing heads and clamping heads, a testing device comprising a member adapted to be moved by changes in pressure, a lever having a long arm and a short arm, the latter being engaged by said pressure actuated member, means for adjusting and limiting the movements of the long arm of the lever, a trip finger connected with the long arm of the lever, an actuating pin adapted to be normally engaged by said trip finger, a cam wheel in engagement with the actuating pin and adapted to rise with each revolution sufficient to permit disengagement of the trip finger, and means carried by the cam wheel for effecting the discharge of cans of a selected type, substantially as described.
